UNITED STATES PATENT OFFICE

2,531,854

HAIRPIN

Gad A. Lambert Linden, Brooklyn, N. Y.

Application June 18, 1946, Serial No. 677,539

1 Claim. (Cl. 132—50)

1

The present invention relates to hair pins and more particularly to that type of hair pin which has become known as a bobby pin.

The bobby pins hitherto known have possessed a number of disadvantages among which are a hair clamping action which is too feeble, or, if the clamping action is sufficiently strong, it has been extremely inconvenient and difficult to open the pin for insertion in the hair.

It is a general object of this invention to provide an improved form of resilient clamping bobby pin which is strong in its clamping action and is formed to provide means by which it may be quickly and readily opened for insertion or removal.

In general the novel bobby pin to be described in detail comprises a continuous resilient strip formed to provide a flared end for receiving the hair, a curved bend or loop for imposing adequate clamping force to two leg portions, and finger engageable extensions continuously engaging and cooperating with the curved bend or loop to provide leverage for easy opening. The clamping legs may be formed with opposed corrugations for the purpose of better retaining the hair.

A more specific object of the invention resides in the provision of a hair pin having features described which may be readily formed from a continuous length of resilient metal or other suitable material by machinery production methods.

These and other features of improvement will be more clearly understood and appreciated from the following detailed description of a preferred embodiment of the invention and several modifications thereof, when taken in connection with the accompanying drawings, in which:

Fig. 1 is a perspective view showing the preferred embodiment of the hair pin being held in open position by a person's hand;

Fig. 2 is a side elevation of the hair pin shown in Fig. 1 in the closed position;

Fig. 3 is an end elevation of the hair pin shown in Fig. 2; and

Fig. 4 shows in side elevation a modified form of hair pin in open position.

With reference to Figs. 1 and 2 which show the preferred embodiment of this invention, it will be observed that the hair pin 10 which is formed of a relatively narrow, continuous strip of resilient material, preferably spring steel, comprises a pair of slender normally engaged clamping legs, designated generally as 12 and 14, having rounded ends 16, 16 which permit ready insertion in the hair and subsequent clamping be-

2

tween closely spread, opposed inner lengths 18, 18 which are formed adjacent the rounded ends with opposed corrugations 20, 20 which will even more positively grip small bundles of hair when the pin shown in Fig. 1 is released to the normally closed position of Fig. 2.

The inner lengths 18, 18 of the elongated legs of the hair pin 10 terminate at their head ends in a relatively small curved bend or loop 22 which is so formed as to urge the legs firmly and resiliently toward each other at all times. As illustrated by Figs. 1 and 2, the approximately circular loop 22 is considerably larger in diameter than the maximum space between the inner leg strips 18, 18 so that the sliding fulcrum contact between the outer sides of said loop and the free end portions of the outer leg lengths 24, 24 will be elemental and a large amount of clear space will be provided for easy opening action. The continuous length of material forming the hair pin 10 is bent outwardly and toward the head portion of the hair pin to provide a straight pair of outer lengths 24, 24, that are only a minor proportion of the length of the clamping leg portions and which in addition to affording a smooth surface and sliding engagement of the hair with the outside edges of the hair pin, are extended or continued a short distance so as to contact opposite sides of the loop 22 and form spaced finger tabs 26. The outer lengths 24, 24 extend substantially parallel to the inner lengths 18, 18. The function of the tabs or grips 26 can be best appreciated from a consideration of Fig. 1 in which they have been moved together about the engaged parts of loop 22 as fulcrums to lift open the two leg portions 12 and 14 against the strong contra-action of the loop 22 and the inner lengths of material 18, 18 connected therewith.

As the modified hair pin shown in Fig. 4 is generally similar to the preferred embodiment which has been described it will be sufficient to note only the principal variations. This modified hair pin 110 includes an opposed pair of identical leg portions 124, 124 and specially formed head end tabs or grips 126 which are curved toward each other and of such a length to overlap as sliding face engaging surfaces. This overlapping is at a maximum when the leg portions 124, 124 are in the open position illustrated and continuous to a much less degree when they assume a closed position. This manner of providing an expandable loop with the tab or grip portions 126 offers some advantages in that there is less likelihood of the adjacent enclamped hair becoming entangled and resisting removal of the hair pin.

While for most purposes it is preferable to make the hair pin of this invention from spring steel strip stock which is uniform in both width and thickness, it is also possible to form the hair pin from other materials having the desired properties of durability, resiliency and formability.

In the principal preferred embodiment and the modification which has been shown, it is to be observed that the hair pin in each instance has no greater overall thickness than that of the uniform width material from which it is formed, that the spring loop also has the full width and strength of this material, and that the finger grips or tabs, which continuously engage the loop, are arranged to provide maximum leverage.

While it is contemplated that the bobby pin of this invention will find particular utility in hair dressing establishments, its neat, compact and efficient attributes will also insure wide acceptance by individual users.

Having thus described my invention, what I claim as novel and desire to secure by Letters Patent of the United States is:

A hair pin formed from a continuous, uniform strip of spring metal to provide an opposed pair of elongated, parallel leg portions having hair-gripping inner lengths joined at adjacent ends by

5 an approximately circular spring loop, and outer lengths forming with the other ends of the inner lengths rounded ends to facilitate insertion of the hair pin, said outer lengths extending in close spaced parallel relationship with the inner lengths and into engagement with the opposite sides of said loop and beyond to afford free end finger tabs for holding the pair of leg portions in open relation, said finger tabs having complementally curved ends arranged in overlapping relation for sliding engagement with each other.
